CUSHION HEAD FOR STAPLING DEVICES

Carl E. Hallen, Mount Prospect, Ill., assignor to
J. B. Crofoot Co., Mount Prospect, Ill., a corporation of Illinois

Application July 21, 1943, Serial No. 495,634

3 Claims. (Cl. 1—48)

My invention relates to a cushion head for stapling devices and the like, designed to be struck by the hand or fist to operate the same.

The object of the invention is to provide a cushion head of the above stated character, designed to replace flexible rubber caps or cushions, which are not available at the present time, due to the demands and shortages of rubber, and which is simple in construction and economical to manufacture, using plenty of available material and a minimum of metal, plastic or equivalent material, and felt or similar soft, pliable padding, shock-absorbing or cushioning material, which may be readily assembled in a novel manner to a plate for attaching the same to the head of a stapling device, punch or similar device, which is struck by the hand, fist or even the palm of the hand, for operating the same, so as to cushion the plate and blow and prevent injury to the hand of the operator.

Another object is to provide novel means to attach or couple the device to the striking, pressure or operating head of the stapling or other device, which means is also constructed to secure firm and proper attachment of the felt or similar cushioning material thereto, to be contacted by the hand in operating the stapler or other device.

Further objects and advantages will appear and be brought out more fully in the following specification, reference being had to the accompanying drawing, in which:

Fig. 1 is a perspective view showing a stapler having an operating or pressure head equipped with the invention.

Fig. 2 is a perspective view of a plate constituting a part of the device for coupling the cushion to the head.

Fig. 3 is a top plan view of the plate shown in Fig. 2.

Fig. 4 is a sectional view, taken on the line 4—4 of Fig. 3, showing the plate and indicating one layer of felt applied thereto, in dotted lines.

Fig. 5 is a similar view showing the cushion fastened in position.

Fig. 6 is a bottom view of the plate, and

Fig. 7 is a fragmentary side elevation showing the cushion applied to an operating head.

Referring to the drawing in detail, in which like reference characters designate corresponding parts throughout the several views, 10 designates a stapling device of ordinary or known form, but may be a punch or like device having a frame with a vertical guideway or sleeve 11, in which a plunger 12 is designed to move up and down. This plunger has a circular, convex or rounded

head 13, constituting an operating or pressure head adapted to be struck in operating the stapler, and is held raised or upwardly disposed as by means of an expandable coil spring 14 positioned between the guideway of the frame and the under side of the head 13, which may be cushioned underneath, if desired, by rubber or the like, felt or other cushioning material.

The edge of the head, which may be riveted to the plunger or shank, may have its edge turned over and under, or may be otherwise suitably formed to give the circular convex shape described.

The anchoring or coupling means for the cushion consists of a circular plate 15 of spring sheet metal, plastic or the like of a concavo-convex formation having a turned flange or edge 16 directed in rounding formation downwardly at right angles, axially away from the convex side 20 and beyond the concave side so as to exactly fit the periphery or rounded edge of the head 13. This plate is formed with suitable, and preferably equi-distantly spaced lugs 17 (shown as six in number), projecting from the edge 16 in the same direction, and preferably rounded as shown in convex formation so as to be bent under the head 13 to retain the plate in position on the head. The plate is also provided with a plurality of pointed tongues or tapered prongs 18 (shown as four in number), suitably spaced preferably equi-distantly, and struck out from the body or metal of the plate to form tapered or triangular cut-outs 19, resulting therefrom when the tongues are bent upwardly, so as to extend axially in a direction opposite that in which the lugs 17 extend, but located within the peripheral edge or area of the plate 15.

To a plate so formed, a layer or ply of felt or similar cushioning or pliable material 20, in the form of a disk, is applied to be pierced under pressure by the tongues 18, as shown in Fig. 4 of the drawing. The ends of the tongues are bent over as shown at 21 in Fig. 5 of the drawing, to securely attach the layer 20 to and in conformity with the convex side or face of the plate, and prevent accidental disconnection thereof.

It is to be understood that the felt disk may be under pressure while applied, but especially while the tongues are being bent, although this is not absolutely essential. The cushioning material may be felt, that is, fabric, compacted by pressure or heat, or other similar soft, compressible material. Any number of layers or plies 55 may be employed to give the proper thickness,

whereby a cushioning action may be obtained, but as shown, an intermediate layer or ply 22, preferably with the fabric loose or less tightly compacted, is preferably employed. This may be fastened to the top of the layer 20 by suitable adhesive or otherwise, as indicated at 23, and a top layer or ply 24 of felt is similarly fastened to the top of the intermediate layer 22. The top layer 24 also is preferably tightly compacted the same as the bottom layer 20, and may have its peripheral edge continuously convexly rounded on top, as indicated at 25, so as to better conform to the palm of the hand, although pressure may be employed in any other suitable way, as by striking the cushion with any soft part of the hand, or even the fist or otherwise, to depress the same and operate the stapler or other device to which it is applied.

It will thus be seen that I have provided a very efficient and economical cushion for the operating heads of stapling devices, punches and the like, adapted to be operated by hand, and that the same may not only be economically constructed, but easily applied, and firmly retain its position.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a cushioning device of the class described, means for attaching laminated cushioning material to the operating head of a stapler, said means including a plate, means on said plate for securing a layer of cushioning material to the plate, and means for securing the plate to the operating head of the stapler or the like.
2. In a cushioning device of the class described, means for attaching cushioning material to the operating head of a stapler, said means including a plate and means on said plate for securing cushioning material to the plate and for securing the plate to the operating head of the stapler or the like, said means consisting of oppositely extending projections, the projections extending in one direction adapted to be bent beneath the operating head of the stapler and the other projections designed to engage a cushion.
3. In a cushioning device of the class described, a plate having oppositely extending projections, the projections extending in one direction being adapted to be bent beneath the operating head of a stapling tool or the like, to secure the plate to the tool, the other projections being designed to connect a cushion to the plate and a cushion adapted to be connected to said plate, said cushion consisting of a plurality of felt-like layers one of which is more compacted than the other layer or layers.

CARL E. HALLEN.
